UNITED STATES PATENT OFFICE

NATHAN WARSHAW, OF BROOKLYN, NEW YORK

CARD FILING CASE

Application filed February 20, 1931. Serial No. 517,278.

The invention relates to filing devices, particularly to cases for index cards and the like and has for its principal object the provision of a simple and readily portable case for pocket use by salesmen and others, domestic use for recipes and the like, for desk or office use or in fact for employment whenever such a device is found necessary or convenient.

10 An important object of the invention is to provide a file case in which the construction is such that the front portion which confines the cards may be moved forwardly so as to permit the cards to be separated and rendered much more accessible for inspection, removal or insertion.

15 A further object is to provide a case of this character which may be formed from a single blank constructed of cardboard, fiber board, leather or in fact any other suitable sheet material, the blank being cut and folded into shape with certain portions permanently secured together as by gluing or the like.

20 Another object is to provide a case of this character provided with an interiorly located reinforcing frame which will increase the strength and rigidity and resist any pressure which might be either intentionally or accidentally exerted upon it in use so that distortion will be avoided particularly if the device be carried in the pocket.

25 A still further object is to provide a case in which the movable card retaining portion is guided in its movement and provided with means which will limit the forward movement and prevent entire disconnection.

30 An additional object is to provide a case which will be extremely simple and inexpensive to manufacture and which may consequently be placed on the market with, possibly, a set of cards, for a few cents, these advantages being in addition to the above pointed out characteristics as regards general efficiency and durability.

35 To the attainment of the foregoing and other objects and advantages, the invention preferably consists in the details of construction and the arrangement and combination of parts to be hereinafter more fully de-

scribed and claimed, and illustrated in the accompanying drawings in which:

Figure 1 is a front elevation of the case in closed position with portions broken away and in section to disclose the cards, 55

Figure 2 is an end elevation with the device closed,

Figure 3 is a front elevation showing the cover open and a portion of the card retaining front broken away with one end and the bottom in section, 60

Figure 4 is a vertical cross section through what is shown in Figure 5 with one of the end portions additionally broken away to show the guide and stop means for the movable front which is represented as in forward position, 65

Figure 5 is a detail fragmentary section on the line 5-5 of Figure 2,

Figure 6 is a view of one half of the blank from which the device is constructed, and

Figure 7 is a view of the other half of the blank showing the preliminary holding of some of the tabs.

Referring more particularly to the drawings I have shown the device as comprising a rectangular case indicated as a whole by the numeral 10 and comprising a back 11, a bottom 12, a front 13, sides or ends 14 and a cover flap 15, all of these parts being integral as the case is formed from a single blank, as shown in Figure 6, in a manner which will be hereinafter described in detail. Of course the size of the case depends upon the use to which it is intended to be put but it is adapted primarily to be made of such dimensions as to accommodate any standard size of card, there being, however, no particular limitation in this respect. Likewise there may be many variations in the material chosen and this would be governed by the contemplated cost of the article. 75 80 85 90 95

In making the case, I take a single piece of sheet material of some suitable sort, for instance light cardboard, and cut it to the proper shape as indicated in Figure 6 to which reference will now be had. This blank comprises a relatively large rectangular central panel which constitutes the back 11, this panel being joined to the bottom forming 100

panel 12 at the line of folding 16. The front member 13 adjoins the bottom forming member 12 at the line of folding 17. The cover 15 comprises a panel 18 which is to form the top and which adjoins the back panel 11 at the line of folding 19, and further comprises a panel 20 constituting the cover flap and which is joined to the panel 18 at the line of folding 21.

10 The sides or ends 14 are of composite form, that is to say they include several elements folded together. The side or end structure comprises panels 22 joined to the ends of the back panel 11 at the lines of folding 23, and 15 further comprises panels 24 adapted to be folded over onto the panels 22 at the lines 25. At one end of each of the panels 24 and separated therefrom by a cut 26 is a tab 27 joined to the panel 22 by the line of folding 28 which is a continuation of the line 25. Each tab 27 is traversed by another line of 20 folding 29, the reason for which will become apparent. Joined to one end of each of the end panels 22 by a line of folding 30 constituting a continuation of the line 16 is a 25 tab 31. These tabs 31 are at the ends of the bottom panel 12 but separated therefrom by cuts 32. At the other end of each of the end panels 22 and joined thereto by a line of folding 33 constituting a continuation of the line 19 is a tab 34. Each tab 34 is traversed by a line of folding 35. The tabs 34 are at 30 the ends of the panels 18 and 20 and are separated therefrom by cuts 36.

35 The front comprises, in addition to the panel 13 above described, other panels 37 joined thereto at the lines 38 which are beyond the cuts 32. These panels 37 are cut away or beveled off at their ends adjacent 40 the tabs 31 as indicated at 39. The other ends of the panels 37 are formed with outwardly extending lugs 40 which operate as 45 stops when the case is folded and assembled as will be described.

50 As a box constructed from sheet material alone does not possess great rigidity, I prefer to provide my case with an interiorly located reinforcing means here disclosed as a U-shaped frame of heavier material than the blank. Actually, fairly thick cardboard is 55 satisfactory for the purpose though other materials may be used if desired. This frame includes a bottom portion 41 and sides 42 as clearly illustrated in Figures 3 and 7.

55 In assembling the case, the panels 24 are folded on the lines 25 to lie against the end panels 22 and the end panels 22 with the panels 24 superposed thereon are folded on the lines 23 to extend at right angles to the 60 main or back panel 11. The frame is then placed in position with its bottom portion 41 lying along the line 16 and with its sides 42 engaging against the panels 24 of the folded sides. The tabs 27 are then folded 65 upon the lines 28 so as to overlie the sides

42 of the frame member and the tabs 34 are folded on the lines 33 to extend across the ends of the members 42. The tabs 31 are then folded on the lines 30 so as to lie against the outer or bottom side of the frame member 41. The panels 37 are folded on the lines 38 to extend at right angles to the panels 13. The parts will then be in the position clearly shown in Figure 7. The bottom panel 12 is folded along the line 16 to lie against the tabs 31 and outer side of the frame member 41, and the panel 13 is folded on the line 17 so as to overlie the frame, the previously upbent end panels 37 entering between the sides 42 of the frame member and the folded together panels 24 and 22 in contact with the inner faces of the former.

70 Assembling further involves folding the tabs 34 inwardly along the lines 35 so that they will lie against the inner faces of the sides 42 of the frame, after which the tabs 27 are folded on the lines 29 so as to lie against the tabs 34 and are secured thereto in any preferred manner, as by gluing. When this is done it will be observed that 75 the tabs 27 overlie the lugs 40 on the panels 37 but are spaced therefrom to permit an action to be described. The above operations define the box which is completed by 80 the simple operation of folding the panels 18 and 20 on the lines 19 and 21 respectively and tucking the free edge or end of the panel 20 beneath the front panel 13 as clearly illustrated in Figures 1 and 2.

85 When the box is completely assembled as 100 above described it is apparent that it is readily adapted to contain index cards as indicated at 43 and will be very convenient for pocket use by salesmen, agents or the like, 105 etc., or for any other use to which index cards may be put. Of course the actual employment of the device does not enter into the essence of the invention but is mentioned 110 simply to disclose the utility. The closed position of the box is shown in Figures 1 and 2 wherein the cover flap or panel 20 is shown as engaged beneath the front panel 13. It should, however, be understood, that 115 snap fasteners or any other equivalent means may be provided for holding the cover closed, this being immaterial. A very important feature is that the front panel 13 is movable toward and away from the back as will be 120 readily observed by comparing Figures 2 and 4. This is permissible owing to the fact that the panels 37 are slidable between the sides of the frame and the ends of the box, forward movement being, however, limited 125 by engagement of the lugs 40 with the inner faces of the bight portions of the folded over tabs 27 as clearly shown in Figure 4. This movability of the front panel permits the cards to be separated so that they may 130 be inspected without removal or removed and

replaced with ease. Clearly the cover may be folded back to as little or as great an extent as may be found necessary, only a partly folded back position being shown in Figures 3 and 4.

From the foregoing description and a study of the drawings it will be apparent that I have thus provided a very simply constructed file case which will be very convenient and efficient in use. Owing to the construction of the device from a single blank, with the addition of the reinforcing frame member, it is apparent that it will be most inexpensive and may be manufactured and sold with a set of cards for a few cents, thereby recommending itself as a commercial proposition. It is thought that the construction, operation and advantages should be quite clear to one skilled in the art without further explanation.

While I have shown and described the preferred embodiment of the invention and a certain definite blank for making it, it should be understood that the disclosure is merely an exemplification of the principles involved and that the right is reserved to make all such changes in the details as will not depart from the spirit of the invention or the scope of the subjoined claims.

Having thus described the invention, I claim:

1. A device of the character described comprising a rectangular case constituting a receptacle and including a back, a bottom, sides, a cover, and a front panel fixed at its lower edge to the bottom and having its upper portion movable toward and away from said back, a U-shaped frame within the case lying against the bottom and sides and secured to the latter, said frame being spaced from portions of the sides to define guides, said front panel having side portions slidably received within said guides and formed at their upper rear corners with stop lugs, and said sides including portions obstructing said lugs for limiting movement of the front panel forwardly.

2. A device of the character described comprising a rectangular case including a back, a bottom, sides, a cover and a front panel, all formed from a single blank, a reinforcing frame of substantially U-shape located within the case against the bottom and sides thereof and secured to the latter, said front panel being swingably mounted with respect to the back and having portions slidably engaged against said frame.

3. A device of the character described comprising a rectangular case formed from a single blank including a back panel, a top cover and closure flap projecting from one edge thereof, side panels formed at the sides of said back and including portions foldable one onto another and further including tabs at the opposite ends, the blank further in-

cluding a bottom-forming panel at the lower edge of said back panel, together with a front-forming panel extending from the opposite edge of said bottom forming panel, said front panel being formed at its opposite ends with side panel members, the sides, bottom and front panel being folded to define a substantially rectangular casing, a frame of U-shape located within the casing and lying upon the bottom thereof and against the sides, the tabs at one end of each of said side panels being folded over onto said frame and onto one another respectively and secured, the side panel members carried by the front panel being slidably received between said frame and the sides of the casing whereby said front panel may be movable rearwardly and forwardly, and means for limiting said movement.

In testimony whereof I affix my signature.

NATHAN WARSHAW.
